GRINDING MILL

Durbin Van Law, Denver, Colo., assignor to
Powderco, Inc., Denver, Colo.

Application December 27, 1932, Serial No. 649,009

4 Claims. (Cl. 83—46)

This invention relates to grinding mills and more particularly to certain new and useful improvements in mills of the type shown and described in my application for Patent Serial No. 5 587,485, filed January 19, 1932, Patent No. 2,031-289, dated February 18, 1936, of which the present application is a continuation in part.

The mill is particularly adapted for feeding a pulverized fuel to the combustion chamber of 10 a furnace and an object of the present invention is to provide a mill in which the fuel is pre-heated by a connection with the burner of the furnace. This burner is the subject of a separate application for patent.

15 The mill comprises a grinding element and a fan-element in cooperative relation, and the improvements comprised in the present application consist mostly in details of construction and an arrangement of parts which render the mill more 20 efficient and practical in operation and construction.

In the accompanying drawings, in the several views of which like parts are similarly designated,

Figure 1 is a sectional elevation of the improved mill,

Figure 2 is a composite view, looking in the direction of the arrows on the line 2—2 of Figure 1,

Figure 3 is a partially sectional top-view of 20 the mill,

Figure 4 is a section taken on the line 4—4 of Figure 1,

Figure 5 is a fragmentary section in the plane indicated by the line 5—5 in Figure 3, and

Figure 6 is a fragmentary section on the line 35 6—6 of Figure 4.

The mill comprises an annular base-plate 5 supported on legs 6 provided with leveling-screws 7. Suspended from the base plate is an 40 electric motor 8 having in connection with its rotor, a shaft 9 extending upwardly in the vertical axis of the annulus. On this shaft are mounted the grinding element A and above the same the fan element B.

45 The last-mentioned element consists of a drum 10 having circumferentially, a plurality of curved vanes 12. The drum is closed at its top and open at its bottom for the admission of fuel carrying air-currents.

50 A hub 13 below the top-plate 14 of the fan, is mounted on the shaft and secured by a key 15.

55 The grinding element has a two-part hub, the inner member 16 of which is connected to the shaft by a key 17 and a set screw 18. The outer

member 19 is connected with the inner member by a shear-pin 20 driven into aligned openings of the members.

Above the hub is a collar 21 fastened to the shaft by a set screw 23, which prevents upward movement of the grinding element when the members of the hub are disconnected by breakage of the pin. The object of the shearing pin is to prevent breakage of the parts of the grinding element, in case its rotary movement is opposed by obstructions or in the event of an overload.

Integrally connected with the outer member of the hub by means of a solid web 24 and spokes 25, is the annular rim 26 upon which are 15 mounted equidistantly, the peripheral vanes or paddles 27. These paddles project over and beyond the top surface and the peripheral surface of the rim and are secured by countersunk machine screws 28. The same screws secure a 20 shroud ring 29, which rests upon the paddles and covers the spaces between the same.

A distinctive feature of the paddles is that their sides forward with relation to the direction of rotation of the grinding element are beveled 25 as at 27a, while their outer edges are beveled inwardly and downwardly as at 27c.

Projecting upwardly from the web of the grinding element, is an annular funnel 30 which abuts against the open bottom plate 31 of the 30 fan element. This funnel and the spaces between the spokes 25 provide a passage for air currents from beneath the grinding element to the interior of the fan element.

A dome-shaped circular housing 32 is fastened 35 upon the base-plate 5 by bolts 33. It encloses the fan element and the grinding element, and it is divided by means of a plate 34 to provide a grinding chamber 35. Between the dividing plate and the top of the housing is a scroll-shaped wall 36 formed integral with the housing and surrounding the fan element in spaced relation thereto. The scroll extends to a peripheral opening of the housing where it connects with a conduit 37 leading to the burner of the 45 furnace. Around the grinding element in spaced relation to the outer ends of the paddles, is a cast iron impact or curb ring 38, and between this ring and the surface of the housing, are wedges 39 of rubber or other resilient material 40 which deaden the sound of the impact.

Upon these wedges and upon the curb-ring 55 rests the dividing plate 34, and upon the dividing plate engages the scroll-wall 36 of the fan-element. Paper gaskets 40 and 41 between the

ring 38 and the plate 34 and between the plate and the lower edge of the scroll-wall 36 provide dustproof and sound deadening packings.

The dividing plate abuts against lugs 42 projecting inwardly from the housing and it is thus held firmly in position without the use of bolts or other fastening devices.

Between the base plate and the impact ring 38 is a bottom plate 43 for the grinding chamber, and again, dustproof and sound-deadening connections are provided by paper gaskets 44 and 45 interposed between the bottom plate 43 and the lower edge of the impact ring and between the bottom plate and the base plate 5.

The bottom plate and the gasket 45 have a series of openings 46 concentric with the shaft, and rotatable on the shaft, is a valve or shutter 47 provided with ports 48 which register with the openings.

20 A handle 49 projects from the shutter beneath the base plate and a bolt 50 on the depending rib 52 allows adjustment of the movement of the handle by engagement with the mounting plate 51 of the motor.

25 The openings 46 and the valve are the media for admitting air to the fan-inlet in regulatable quantities.

At the periphery of the rim of the grinding element, between the paddles, are bosses 53 functioning as projectors which in the operation, return coarser particles of the material into the path of the paddles until they are reduced to the desired size.

It is to be noted that the grinding element is separated from the bottom plate by a space 54, which, together with the velocity of the air currents admitted through the openings of the bottom plate, determines the fineness to which the fuel is reduced.

40 In the operation of the mill, the material is fed onto the dividing plate through an opening 55 in the dome of the housing and thence passes through openings 56 in the dividing plate onto the web 24 of the grinding element, from where 45 it is thrown into the spaces between the paddles and against the impact ring, it being understood that the two elements mounted on the rotor shaft are rotated at a comparatively high velocity.

50 The grinding-vanes reduce the material to a fineness which permits of their passage through the space 54 between the rim of the grinding element and the bottom plate 43 of the grinding chamber, to be carried upwardly by the air currents drawn through the air-openings 46 by the movement of the fan. The fuel-laden currents are thrown outwardly through the spaces between vanes of the fan into the scroll wall 36 to be drawn through the conduit 37 to the burner of 60 the furnace.

Heated air from the furnace may enter the housing through an opening 57 and not only aids in the movement of the fuel, but also pre-heats the same before it enters the burner of 65 the furnace.

The form of the blades 21 of the grinding element is of importance in the operation, since they provide for the comminution of the material, both by impact and by attrition.

70 The upper portions of the blades provide impactors, which, in cooperation with the ring 38, reduce the material by impact.

The bulk of the material accumulates in the 75 spaces provided by the lower, beveled portions

27c of the paddles, and is there reduced by attrition. The shroud ring 29, covering the spaces between the paddles, prevents "back firing" of the material, there being a tendency of coal dust to rise and back up through the air ports or through the feed-pipe. This shroud ring is essential to the satisfactory operation of the mill. The projectors 53 throw coarse particles in the material back into the path of the bulk of the material until they are reduced to the desired 10 size.

The shutter 47 regulating the size of the openings 46, is of importance since the inflow of air determines the grinding period and thereby the fineness to which the material is reduced. The 15 construction of the mill combines practicability with simplicity and low cost of production.

The one-piece housing encloses all the working elements, it includes the fan scroll as an integral part, and it provides for securing the 20 division plate, and the impact-ring.

The operation is rendered practically noiseless by the provision of the paper gaskets and the rubber wedges. All of the parts are easily removed and replaced in case of wear and 25 breakage, and by making the parts of light metal, such as aluminum, the entire device may be made portable.

The sheer pin prevents breakage in the event of an overload or the introduction of foreign objects with the feed, and when the pin is broken, the safety collar 21 prevents the grinding wheel from moving upwardly on the shaft.

What I claim and desire to secure by Letters Patent is:

1. In a grinding mill, a housing having a circular impact surface, a base, a grinding chamber, a rotor in the circle of said surface spaced from said base and having vanes projecting outwardly from its peripheral edge, a passageway 40 or conduit formed through said rotor, a shroud-ring on the rotor closing the spaces between the vanes, the periphery of the shroud-ring being substantially coincident with the outer edge of the vanes, the space between the rotor and base 45 communicating with said passageway and together forming a continuous passageway from the grinding chamber through the rotor, and suction means for the upward movement of ground matter through said continuous passage- 50 way.

2. In a grinding mill, a grinding chamber with a flat chamber wall, a housing having a circular impact surface and having an outlet for the product of the grinding action, a rotary grinding 55 element within the circle of said surface, spaced from a wall of the housing to admit the product of the grinding action, said rotary grinding element having an imperforate annular portion, annular guiding and deflecting means spaced above said imperforate portion and rotatable therewith, the grinding chamber located on one side of said imperforate portion, a passageway located in the grinding element on the other side of the imperforate portion, the annular 65 imperforate portion being located with an edge adjacent a flat chamber wall to define an entrance for air and ground material from the grinding chamber to the passageway, feed and air inlet means for the grinding chamber and 70 suction means connected with the passageway for drawing air-borne ground material from the grinding chamber through the entrance and passageway.

3. A grinding mill comprising a flat walled 75

base, a housing internally shouldered, a partition fitted against the shoulder of the housing and separating the housing into a grinding chamber and a suction chamber, a rotary grinding element within the grinding chamber, said rotary grinding element having an imperforate annular portion, the grinding chamber located on one side of said imperforate portion, annular guiding and deflecting means spaced above said imperforate portion and rotatable therewith, the grinding element being spaced from said base and provided with a passageway therethrough on the other side of the imperforate portion, the annular imperforate portion being located with an edge adjacent a flat chamber wall to define an entrance for air and ground material from the grinding chamber to the passageway, feed and air inlet means for the grinding chamber, a suction element in the suction chamber connected with the passageway for drawing air-borne ground material from the grinding chamber through the entrance and passageway.

4. A grinding mill comprising a housing, a base, a grinding chamber in the housing, a rotary grinding element in the grinding chamber spaced from the base and a wall of the housing to admit the ground product, said rotary grinding element having an imperforate annular portion, a grinding chamber located on one side of said imperforate portion, annular guiding and deflecting means spaced above said imperforate portion and rotatable therewith, a passage through said grinding element, the space between the grinding element and the wall and the base communicating with said passage, a suction chamber, a suction element in the suction chamber whereby the ground product is conducted from the grinding chamber directly to the suction element, and means to adjust the grinding element relative to a wall of the housing to vary the space between the grinding element and the base, and thereby vary the thickness of the ground product. 5 10 15 20
